UNITED STATES PATENT OFFICE.

PRINCE E. SHORTT, OF FLOYD, VIRGINIA.

COMBINATION-TOOL.

No. 921,171.

Specification of Letters Patent.

Patented May 11, 1909.

Application filed August 4, 1908. Serial No. 446,874.

To all whom it may concern:

Be it known that I, PRINCE E. SHORTT, a citizen of the United States, residing at Floyd, in the county of Floyd and State of Virginia, have invented a new and useful 5 Combination-Tool, of which the following is a specification.

This invention relates to compound tools of the auger type and its object is to provide 10 a tool of this character made up of adjustably connected members designed to be adjusted to various positions with respect to one another, and to be assembled in different ways to enable the device to be used for various purposes, such, for example, as an auger, 15 a vise, a wrench, a wire-cutter, etc.

Another object is to provide an auger having a detachable handle section designed to be secured in position in a simple and efficient manner and which can be readily discarded when the tool is to be used for other purposes.

With these and other objects in view the invention consists of certain novel details of 25 construction and combinations of parts hereinafter more fully described and pointed out in the claims.

In the accompanying drawings the preferred form of the invention has been shown.

30 In said drawings:—Figure 1 is a side elevation of the tool with parts so assembled as to enable the same to be used as an auger. Fig. 2 is a view partly in side elevation and partly in section showing the parts of 35 the tool arranged for use as a wrench, one of the positions of the handle being shown by dotted lines. Fig. 3 is a side elevation of the tool in position for use as a vise, the jaws of the vise being shown in another position by 40 means of dotted lines. Fig. 4 is a perspective view of the threaded stem used for attaching the handle to the tool, said stem, when detached, as shown in said figure, being designed to be used as a screw-driver. 45 Figs. 5 and 6 are elevations of the inner or adjoining faces of the two heads of the tool. Fig. 7 is an end view of the grip of the auger. Fig. 8 is a bottom plan view of the coupling member of the knob of the auger. Fig. 9 is 50 a perspective view of the coupling at one end of the shank. Fig. 10 is a detail view of the pivot pin used in connection therewith. Fig. 11 is a side elevation of a portion of the 55 tool and showing a ratchet bit socket in position therein.

Referring to the figures by characters of reference, 1 designates the main shank of the tool, said shank being provided at one end with a head 2 preferably integral therewith and having integral jaws 3 and 4 formed by the end portions thereof. The working face of the jaw 4 is concave as indicated at 5 and provided with transversely extending teeth, while the working face of the jaw 3 is formed with a series of transversely extending teeth 6 preferably arranged diagonally as indicated in Fig. 6. A head 7 is slidably mounted on the shank and the ends of this head form jaws 8 and 9 designed to coöperate with the jaws 3 and 4. Jaw 9 has a series of transversely extending teeth 10 upon its working face, while the jaw 8 which is located directly opposite the jaw 3, is provided with a series of diagonally extending teeth 11. Oppositely disposed recesses 12 are formed within the working faces of the two jaws 3 and 8 and extending from these recesses, which are preferably substantially semi-spherical, are 70 grooves 13 triangular in cross section and gradually increasing in width and depth toward the free ends of the jaws 3 and 8. Smaller grooves 14 connect the broad ends of the grooves 13 with the ends of the jaws 3 and 8, as clearly indicated in Figs. 5 and 6. When the two jaws 3 and 8 are brought together the recesses 12 and the grooves 13 and 14 register to form a socket, and this socket is designed to receive the head of a bit, not shown. The jaws 4 and 9 are especially 75 designed to engage pipes and other round objects, and, by reason of the peculiar contours of the working faces of these jaws, they will firmly grip thereon.

Arranged upon that end of shank 1 farthest removed from the head 2 is a cross-head, 15, one end of which forms an arm 16 in which is swiveled the stem 17. One end of this stem is provided with a milled head 18 whereby said stem can be readily turned by hand. The greater portion of the stem is 80 screw-threaded as indicated at 19, and extends into and engages the threaded opening 20 extending through the jaw 8. Obviously by rotating this stem 17 the threaded portion thereof will operate to feed the head 105 7 toward or from the head 2.

The other end of the cross-head 15 is enlarged as indicated at 21 and provided with a transverse slot 22, which divides said end portions into two similar ears. Central open- 110

ings 23 are formed within these ears and are designed to receive a pivot pin 24 having a flat face 25 extending longitudinally thereon and terminating at a shoulder 26. This pin is slidably mounted within the openings 23 and is limited in its movement by the head 27 of the pin and by the shoulder 26, there being a stop pin 28 projecting into one of the ears and contacting with said flattened face 25. This pin will obviously not only limit the longitudinal movement of the pin 24, but also prevent said pin from rotating within the enlargement 21. The enlargement 21 has transversely extending shoulders 29 and 30 arranged thereon at about one hundred and eighty degrees apart and those portions of the enlargement which are located between the shoulders are rounded as shown at 31.

20 V-shaped lugs 32 are arranged upon these rounded portions and at points equi-distant from the shoulders 29 and 30. These rounded portions between the shoulders and the projections 32 constitute seats for a collar 33 formed at one end of a sleeve 34. The end face of said collar is so shaped as to fit snugly upon the rounded portion of the cross-head and against the shoulders and projections as clearly indicated in Figs. 1 and 2. A head 35 is formed at the end of sleeve 34 farthest removed from collar 33, and revolvably mounted upon the sleeve between said head 35 and the collar 33 is a grip 36. A recess 37 is formed in the one face of the head 35 and is 35 for the purpose hereinafter set forth.

40 Pivottally mounted upon the pin 25 and within the slot 22 is a ring 38 having a cutting nose 39 extending from the periphery thereof and designed to coöperate with the shoulder 30 for the purpose of cutting wire. A screw-threaded stem 40 extends from this ring 38 and close to the nose 39, said stem having its free end beveled as at 41 so as to constitute a screw-driver. A nut 42 is 45 mounted upon the threaded stem and is for the purpose hereinafter set forth.

50 The stem 40 is designed to extend through a tubular head 43 formed at one end of a crank-arm 44 on which a knob such as is ordinarily used in connection with augers is mounted, as indicated at 45. The nut 42 is designed to turn against the head 43 so as to firmly bind it against the head 35, and, in order that the crank-arm 44 may be held 55 against independent movement relative to the sleeve 34 and the head 35, a lug 46 is arranged upon the head 43 and is designed to be seated within recess 37 as clearly indicated in Fig. 1.

60 As heretofore stated the tool herein described is primarily designed for use as an auger. When the parts are assembled as indicated in Fig. 1 the jaw 8 can be adjusted away from the jaw 3 by means of the feed screw 19 and after a sufficient movement of

the jaw has been obtained the head of a bit, not shown, may be placed between the two jaws 3 and 8, so that when jaw 8 is adjusted back toward the jaw 3 the head of the bit will become seated within the angular recesses 13 and the groove 14.

70 When the parts have thus been assembled the knob 45 can be placed against the body and the operator by taking hold of grip 36 can revolve the device so as to properly rotate the bit held thereby. By shifting the position of the crank-arm 44 so that it will extend in the opposite direction from the grip 36, or, in other words, so that the crank-arm 44 and the shank 1 will extend in opposite directions, the tool constitutes an efficient device for cutting and cleaning horses' hoofs, because a suitable sharp blade can be clamped between the jaws 3 and 8 and the knob 45 held against the body while said blade is being manipulated. By removing the nut 42 the crank-arm 44 can be slid off of the threaded stem 40, and said nut can then be replaced upon the stem and screwed 80 against the head 35 of sleeve 34.

90 With the parts thus assembled the tool can be used as a wrench and, if desired, the grip portion 36 can be placed in a line parallel with the shank as shown in full lines in Fig. 2 simply by sliding the grip 36 longitudinally 95 on the stem 40 until said grip becomes disengaged from the shoulders and projections on the enlargement 21. The handle or grip can then be swung either into the position shown in full lines or into the position shown in dotted lines in Fig. 2, and after this position has been obtained the grip can be shifted against the enlargement 21 so that its collar 33 will be seated between the projections 32 and either the shoulder 29 or the shoulder 30. 100 By screwing the nut 42 on to the stem 40 the grip will thus be securely held against displacement.

105 Obviously, by rotating the screw 19 the jaws 8 and 9 can be adjusted toward or from the jaws 3 and 4, and by reason of the peculiar construction of these jaws, they can be used either to grip nuts, or pipes and similar round objects.

110 One of the important features of the present invention is the fact that it can be readily used as a vise. This has been clearly indicated in Fig. 3. The table "A" on which the vise is to be used is provided with an opening "a" designed to receive the stem 40. After 115 the stem has been placed in this position the grip 36 is replaced upon the stem with collar 33 in contact with the bottom surface of the table-top. The nut 42 is then screwed on to the stem 40 so as to bind the collar 33 of the grip against the lower face of the table "A." As shown in full lines in Fig. 3 the vise can be 120 placed with the jaws 4 and 9 in contact with the table and with shank 1 extending at right angles to the stem 40. When in this position 125 130

the shoulder 30 and the projections 32 will bear upon the top of the table. The efficiency of the jaws 3 and 8 in this connection is greatly increased by the provision of a transverse groove 47 in the working face of the jaw 3 so that small objects such as nails and the like can be securely held between the jaws 3 and 8. This is especially desirable where it is designed to bend or upset nails, or to form staples, etc. It will also be noted that the working faces of the two jaws 3 and 8 are provided with straight transversely extending teeth 48 which are located at the inner ends of said working faces. These teeth are found to be very desirable in holding some forms of work.

Under some conditions it is desirable to have the jaws of the vise adjustable vertically and beyond the edge of the table. With the present invention this is possible by loosening the vise and swinging the cross-head 15 so that it will assume a position at right angles to the stem 40. Such an arrangement has been indicated by dotted lines in Fig. 3, and when the parts are thus positioned the projections 32 and the shoulder 29 bear upon the table.

Among other uses to which this tool may be put are those of a wire-cutter and a screw-driver. To cut wire the collar 33 is adjusted away from the enlargement 21 so as to expose the nose 39. The wire to be cut is then placed against the curved portion of the enlargement 21 and between the extensions 32 and the shoulder 30. By swinging the stem 40 upon its pivot-pin 24 the nose 39 will force the wire against the shoulder 30 and cut it. It is of course to be understood that this shoulder 30 is intersected by the slot 22 so as to permit the nose 39 to move past it.

To use the tool as a screw-driver the pin 24 is slid outwardly as far as it can be moved, and this movement will be sufficient to release the ring 38. The stem 40 can thus be detached from the rest of the tool, and, by removing the nut 42, the grip 36 and the parts combined therewith can be withdrawn from the stem 40. By replacing the nut 42 on the stem and close to the ring 38 the device will have the appearance indicated in Fig. 4, and can be conveniently used as a screw-driver.

It will be seen that this device is very compact and efficient and will be found very desirable because of the number of different uses to which it may be put. Considering its usefulness and the numerous functions ascribed to it, the tool is formed of comparatively few parts, and these parts will not easily get out of order.

Obviously various changes may be made in the sizes and proportions of the parts without departing from the spirit or sacrificing the advantages of the invention.

As shown in Fig. 11 a ratchet bit socket,

such as indicated at 49, may, if desired, be secured between the jaws 3 and 8.

What is claimed is:—

1. A compound tool comprising a shank, gripping members carried thereby, a cross-head upon the shank, said head having ears each provided with a bearing shoulder and a bearing lug, a stem pivotally mounted between and extending beyond the ears, a grip movable longitudinally upon the stem, means movable with the grip for frictionally engaging the bearing shoulder and lug, said grip, means, shoulder and lug constituting support engaging devices, and means for shifting the grip longitudinally upon the stem, and for holding it against movement. 70

2. A compound tool comprising a shank, gripping members carried thereby, a cross head upon the shank and having spaced ears, said ears being provided with a bearing 85 shoulder and spaced bearing lugs, a stem pivotally mounted between the ears and extending there-beyond, a grip slidably mounted upon the stem, a collar carried thereby and shiftable into engagement with the bearing shoulder and lugs, said shoulder, lugs and collar constituting means for gripping opposite faces of a supporting structure, and means engaging the stem for shifting the grip relative thereto and holding the collar 90 in engaging position.

3. A compound tool comprising a clamping structure including a shank, a cross-head upon the shank, said cross-head having spaced marginal bearing shoulders, a stem 100 pivotally connected to the cross-head, a grip movable longitudinally upon the stem, means movable with the grip for projecting between and frictionally engaging the bearings, said grip, means and bearings constituting support-engaging devices, and means for shifting the grip longitudinally upon the stem and for holding it against movement. 105

4. A compound tool comprising a shank, clamping members carried thereby, a cross 110 head upon the shank and having spaced projecting portions, a stem pivotally mounted between and extending beyond the said projections and having an integral nose co-operating with one of said projections to constitute a wire-cutter, a grip slidably mounted on the stem, a collar movable therewith and shiftable into engagement with said projecting portions to hold the grip and stem against movement relative to the cross head, and 115 means engaging the stem for locking the collar and cross head in engagement.

In testimony that I claim the foregoing as my own, I have hereto affixed my signature in the presence of two witnesses.

PRINCE E. SHORRT.
